UNITED STATES PATENT OFFICE

GEORGE VAN STEENBURG, OF ORLANDO, FLORIDA

SEWAGE-DISPOSAL TANK

Application filed May 22, 1929. Serial No. 365,049.

This invention relates to a structure for the sanitary treatment and disposal of sewage matter, the same being primarily intended for use as an outside privy, as well as for the treatment of house sewage such as under ordinary conditions is discharged from city residences and the like into modern sewage systems.

In carrying the invention into actual practice, I have evolved and produced what I believe to be an economical, simplified and practicable form of privy which comply with the needs and requirements of devices of this class, such as are principally intended for use in rural districts.

My idea includes the embodiment of a sectional concrete box or tank which is partly submerged in the ground, the same being used in association with an appropriately constructed house, the house being such in construction as to cover and protect the specific portions of the tank and the rear half being projected to the exterior where it is rendered accessible for periodical cleaning.

In accordance with the invention, the exposed part of the tank is provided with a removable slab or cover which facilitates the cleaning operation and associated with and rising from this is a vent forming stack which is also located on the exterior, all features cooperating in a dependable manner to render the structure unusually sanitary and less likely to the attraction of flies and other insects and pests.

Other features and advantages will become more readily apparent from the following description and drawings.

In the drawings:

Figure 1 is a view in section and elevation of the complete structure showing the relationship of parts.

Figure 2 is a top plan view of the privy per se.

Figure 3 is a front elevational view of the same.

Figure 4 is a transverse vertical section on the line 4-4 of Figure 1.

Referring now to the drawings by reference numerals it will be seen that 5 designates generally a substantially rectangular

box like tank, the lower half of which is intended to be submerged or embedded in the ground 6. The reference character 7 designates generally an appropriately constructed house, to protect the user. 55

This is of somewhat usual design and includes an entrance 8. It is to be observed that this house is so made as to allow the forward corner portion only of the tank and its accessories to project into the interior of the house. 60

The remaining rear corner is disposed to extend beyond the rear wall 9 of the house, as clearly seen in Figure 1. The tank is open at its bottom as seen in Figure 4 and made up of front and rear walls 10 and 11, as seen in 65

Figure 4, and end walls 12, cooperating therewith. The abutting ends of these walls are interlocked by mortised joints of the type shown. This permits the walls to be precast and carried to the job to be set up in a convenient and expeditious manner. These 70

interlocking joints, generally designated by the reference character 13, as shown for example in Figure 3. The closing top comprises two independent slabs, the front slab 75

14 is disposed on a horizontal plane and provided with inlet apertures or openings 15. The rear slab which is inclined downwardly and outwardly is designated by the reference character 16. This slab, as is obvious in 80

Figure 1, is located on the exterior of the building and serves to shed water onto the ground. It carries the vent forming stack 17 which is also located on the exterior of the building and of any appropriate construction. 85

In actual practice, it has been found convenient to provide the top with an insect screen (not shown). Both of these slabs are bodily removable. The slab 16 is removable to permit access to be had to the interior for 90

cleaning.

The front slab is made removable in order that the accessories may be fastened thereon. For instance, the accessories comprising in each instance, a suitably shaped seat board, 18, disposed over the complementary opening 15, a hinged strip 19, and hinged cover 20. The stationary parts 18 and 19 are fastened by bolts 21, to the concrete slab. This ar- 100

arrangement facilitates the manufacture and construction of the device.

Various changes in the specific size, shape and arrangement of parts may be resorted to, without departing from the spirit of the invention or the scope of the appended claim.

It will be observed that a feature of great importance in my invention lies in the construction of the tank. The four vertical walls of the tank are molded separately and provided with interlocking members at their edges, so that when they are brought together to form a box-like tank they form a solid unitary structure. One advantage of this is that a base or foundation for the walls is rendered unnecessary as it will be impossible for the walls to separately settle into the earth, and another advantage is that the surrounding earth holds the walls in interlocking relation. A further advantage is that the walls may all be constructed separately in a shop and transported in that condition to the location of the tank and there assembled.

What is claimed is:

25 In an apparatus of the class set forth, a tank made of precast concrete slabs partially embedded in the ground and embodying front, rear and end slabs formed with means at their vertical edges for locking them together when assembled in a box-like shape, said rear slab being of less height than the front slab and the top edges of said end slabs being inclined downwardly and rearwardly for a portion of their length, a front and a 30 rear top slab also precast and supported by the vertical slabs, said rear top slab being positioned on the inclined portion of the end walls and said front top slab being formed with seat openings, and a housing covering the front upper portion of said tank leaving the upper rear portion exposed outside of the housing for the purposes set forth.

In testimony whereof I affix my signature.
GEORGE VAN STEENBURG.
